AIRLINE RADIO BEAM GAME

Frederick D. Clarke, Manhasset, N. Y.

Application November 22, 1937, Serial No. 175,750

3 Claims. (Cl. 273—134)

This invention relates to games and more particularly to games of the type which utilizes movable pieces, such as a representative airplane, to be moved a certain number of spaces as indicated by a spinner. More particularly the game simulates the competitive movements of the two, three or four aircrafts flying from different points along radio beams to a given destination or common airport.

An object of this invention is to provide a game board having given locations situated along a direct line or radio beam, at which the player or pilot, receives instructions regarding the flight of his airplane or moving piece, said instructions being to either impede or advance the movements of the various competing airplanes.

A further object is to provide a playing field on which any one or more of several competing pieces, or airplanes, moves in a substantially straight line from the time of leaving a representative airport until arriving over another common airport, which is the destination, said line of flight being similar to the course followed by an airplane which is traveling on a radio beam course.

A still further object is to have each airplane start the flight at the landing field of origin by symbolically flying at one altitude and then symbolically come down to a lower altitude before being able to complete the journey on to the landing field at the airport of destination.

Other and further objects will become apparent during the relation of certain features of construction and arrangements of parts to be hereinafter fully described and illustrated in the accompanying drawing and more specifically pointed out in the appended claims.

In describing the invention in detail reference may be had to the drawing wherein like characters denote like or corresponding parts throughout the several views.

In the drawing:

Fig. 1 is a plan view of the game board with a showing of one representative playing piece comprising a miniature airplane and a removable base portion or support.

Fig. 2 is representative of the manner in which the players or pilots will be instructed to receive certain flying orders, and special instructions.

Fig. 3 is a spinner such as may be used to indicate to the players or pilots the number of spaces or units they may advance.

Referring particularly to Fig. 1, the general outline of the main playing field is similar to a St. Andrews cross, comprising four legs represent-

ing independent routes of travel from four different points of origin, namely, as shown, Montreal, Cleveland, Boston and Washington, each route having a common terminus, as herewith shown to be Newark.

The playing pieces consist of a base such as 4, having a spindle 5, supported thereon, said spindle 5, having a limiting collar 6, attached thereto which collar 6 abuts the under side of a miniature airplane 7, having an aperture 8, therein for receiving the free end of the spindle 5. The purpose of the removable base 4, for the airplane 7, is to afford interchangeability so that an airplane may use one of several bases during the game to simulate flying at various altitudes to cope with weather conditions and flying orders, the various bases having numerically indicated thereon the representative altitude in feet for each base. Therefore each player would be provided with, say, four differently marked bases, and one airplane of a distinctive color.

Under actual flying conditions airplanes flying in certain directions may be instructed to fly at "even" altitudes such as 4,000, 6,000 or 8,000 feet, while airplanes flying in an opposing direction may be instructed to fly at "odd" altitudes, such as 3,000, 5,000, 7,000 or 9,000 feet. Further it is generally recognized practice, that when an airplane equipped with radio, is about to enter a properly supervised airport, the pilot of said airplane is instructed to come down to say 2,000 feet altitude and then proceed to land. It is clear then, that each of the four players would have for his distinctively colored airplane, one base for 2,000 feet, and several bases for higher altitudes. On the playing board 9, two points of origin, namely Montreal 2, and Boston 4, respectively are designated as requiring flights at even altitudes as suggested by the characters 2 and 4, while Cleveland 1, and Washington 3, respectively, are designated as requiring flights at odd altitudes as suggested by the characters 1, and 3. Therefore, Montreal and Boston pilots would have say, four bases designated as 2,000, 4,000, 6,000 and 8,000 feet while the Cleveland and Washington pilots would have bases for their airplanes of say, 2,000, 3,000, 5,000 and 7,000 feet.

The game in actual practice requires each player to receive a minimum of five messages from the various flight superintendents or other designated officers, which messages are written on cards addressed to the pilot and signed by a proper officer such as the flight superintendent. These cards (not shown) are suitably assorted and placed on the proper square, as the airline

dispatch office, D, airline radio station, A'', U. S. Government radio station, B', and Newark airport radio station, C'.

The radio beams are symbolically defined by lines or boundaries 16 and 16', which converge at the Newark Radio Transmitter at the "cone of silence," which in fact is a "dead spot" for radio reception from the government radio range or radio beam station located adjacent the Newark airport.

To begin the game, the first player may be determined by having the player getting the highest number on the spinner be the one to start. Assume Montreal is first to start. The player then spins and since he is flying on the Montreal-Newark radio beam, which is on an even altitude radio beam, he must get an even number as a 2 or 4. Upon getting either a 2 or 4, he then goes to the airline dispatch office for instructions, that is, he picks the top card which may read as follows: "Late passenger—hold flight—lost turn." The next time the Montreal pilot gets a turn he spins the pointer 10, pivotally mounted on 11, at point 12, and must again get a 2 or 4 to enable said pilot to get further instructions from the airline dispatch office. Assume that this time the dispatch office message reads, "Clear weather—start flight at 6,000 feet—take extra spin." The pilot would then put his airplane on a base reading 6,000 feet altitude, and take the extra spin and consequently moving the airplane the designated number of spaces, which are marked 14.

Since there are four spaces embraced by the block 13, of the various radio stations such as A—A' and B, it is clear that with the spinner as shown not having a number thereon higher than 4, each player is bound to get at least one message from each of the stations. This is also true of the Newark airport spaces embraced by the block C.

When the player reaches a space 14, embraced by block 13 of A, he must receive another message, this time from the airline radio station. The instructions for each block antenna such as A and A', is placed on the symbol of the antenna, as shown at Fig. 2, but actually not shown on the board 9, to preserve clarity in description and legend. The instruction or legend on B is "Receive message from U. S. Government radio station," and placed thereon in a manner similar to Fig. 2.

Between A and A' there is a space designated as 15, and another space between B and the "cone of silence," shown as 15', which spaces are representative of, and shown by legend as, emergency fields, said "cone of silence" shown as dotted circle.

Each player in turn, moves off the A 13 block, and eventually arrives on A' 13 block, which 60 has the same instructions which are followed by certain statements as, lose turn, take extra spin, move ahead or move back to nearest emergency field, etc.

When the player reaches B, the instructions in message form from the U. S. Government radio station may be favorable or unfavorable to the progress of the playing piece toward the ultimate goal which is the block 17, or Newark airport. However, before the pilot can proceed past block 13 of B, a message must be received via the card set on B' stating in substance that conditions are favorable and to come down to 2,000 feet altitude. Consequently no airplane can move into or through the cone of silence 75

without receiving specific instructions to do so. This station, B, ultimately causes all planes to lower their altitude to 2,000 feet, before landing at Newark airport.

5 In turn the player by spinning, must move through the cone of silence onto the approach leg 20. If the player lands in the square, marked as the cone of silence, the legend shows that he gets an extra spin, to enable him to get out of this area, since in actual practice only one airplane is permitted to land at one time, while the remaining airplanes must circle overhead until the runway is cleared of airplane traffic, at which time the pilots still in the air must individually receive instructions regarding their next maneuver.

When the player reaches the block of four spaces embraced by C, he must receive a message, that is, take a card from rectangle C', which is shown by legend to be the Newark airport radio station. The instructions here will indicate to the player pilot just how he is to land his plane, that is the instructions will be such as "land south," or "circle field and land north," etc. The characters N, E, S and W indicate north, east, south and west respectively.

From the foregoing it will be seen that the maneuvers practiced by the pilot flying the Montreal-Newark radio beam will be the same for the remaining pilots flying from Cleveland, Boston and Washington to Newark on their respective radio beams.

In order to actually have a player land at the Newark airport, 17, a player pilot must receive the exact number on the spinner corresponding to the number of spaces left within the spinner range, counting 17 as a space, to finish the game. In other words, if a player assigned to land north, stops on the space marked N, moving his airplane in accordance with the spinner number, his next spin must be a 2 in order for the player to reach the Newark airport on that spin. The first player to reach objective 17 is the winner, while the other players accept the position of finish in the order in which they actually reach the Newark airport. The exact messages for the players are not presented herewith, since it is clear that any suitable messages may be used in order to convey to the player pilots the desired information and instructions for the operation or playing of the game.

From the foregoing it will be seen that a great variety of movements may be accomplished, and in actual practice a player may receive instructions several times during flight to either increase or decrease his altitude, say 2,000 feet, to meet certain conditions, all of which necessitates the use of the various bases for the several specific altitudes.

The hangars, or points of origin, as 1, 2, 3 and 4, each have a single representative or suggestive letter thereon, as C, M, W and B for Cleveland, Montreal, Washington and Boston respectively, while the part 21, which is the same on all hangars, is representative of a wind sock which is used in actual practice to indicate the general direction of the wind.

While specific details of the invention have herein been shown and described, the invention is not confined thereto as changes and alterations may be and may become apparent to those skilled in the art without departing from the spirit thereof as defined by the appended claims.

Having thus described the invention, what I

claim as new and desire to secure by Letters Patent of the United States is:

1. In an amusement device, a plurality of major straight playing courses extending radially inwardly to a common central space and each of said courses being divided into playing spaces, and a separate terminal course having a straight portion and a final portion defining a closed continuous path and enclosing a winning space, both of said portions being divided into playing spaces, said straight portion extending outwardly from said central space and having its outermost playing space in common with a playing space of said closed continuous path portion.

2. In an amusement device, a plurality of major straight playing courses extending radially inwardly to a common central space and each of said courses being divided into playing spaces, and a separate terminal course having a straight portion and a final portion defining a closed continuous path and enclosing a winning space, both of said portions being divided into playing spaces, said straight portion extending outwardly from said central space and having its outermost playing space in common with a playing space of said closed continuous path portion,

5 and said continuous path portion being so constructed and arranged that only certain determined ones of the playing spaces of said continuous path portion constituting approach spaces afford access to the winning space enclosed by said continuous path portion.

3. In an amusement device, a plurality of major straight playing courses extending radially inwardly to a common central space and each of said courses being divided into playing spaces, and a separate terminal course having a straight portion and a final portion defining a closed continuous path and enclosing a winning space, both of said portions being divided into playing spaces, said straight portion extending outwardly from said central space and having its outermost playing space in common with a playing space of said closed continuous path portion, chance determining means for indicating the number of playing spaces to be played, and the number of playing spaces on said straight portion of said terminal course being at least equal to the maximum number of moves determinable by said chance determining means.
